Bartlett & Munroe.

UNITED STATES PATENT OFFICE.

ALBERT GUTH, OF PERTH AMBOY, NEW JERSEY.

OUTLET-BOX.

1,304,040.

Specification of Letters Patent. Patented May 20, 1919.

Application filed May 1, 1916. Serial No. 94,562.

To all whom it may concern:

Be it known that I, ALBERT GUTH, a citizen of the United States, residing at Perth Amboy, county of Middlesex, State of New Jersey, have invented certain new and useful Improvements in Outlet-Boxes, of which the following is a full, clear, and exact description.

My invention relates to improvements in outlet boxes and has for its object to provide an outlet box to which all standard fixtures and fittings may be directly secured, thus doing away with the necessity of installing a different box for different fixtures or fittings and the removal of one box and substitution of another when it is desired to use a fixture different from that originally planned for, and an outlet box, which, when secured to a beam or joist, will have all its parts flush with or embedded in the plaster of a wall or ceiling. My box is such that it has an integral stud on which a fixture can be screwed, but which does not interfere with the securing or use of a flat cover or a fitting having a flat base, thus making it of a universal character of very wide use. It further has for its object to provide an outlet box having a fixture supporting stud and knock-out holes adapted and arranged to permit the use of various sized cables or conduits, such as are now in common use, and of nipples and connectors for the conduits and cables.

The following is a description of an embodiment of my invention, reference being had to the accompanying drawings, in which:

Figure 1 is a plan view of an outlet box embodying my invention;

Fig. 2 is a section with a flat base fitting, partly in section, applied thereto.

Referring more particularly to the drawings, my outlet box consists of an integrally cast bottom 1 and wall 2, the bottom being provided with a short screw threaded stud 3 cast integral therewith. This stud is shorter than the height of the wall so as not to extend to its edge, and serves to support a depending fixture screwed thereon. This stud has sides in line with its screw-threads rising abruptly from the bottom of said box. Projecting inwardly from the wall are two lugs 4-4 extending from the bottom of the box to approximately the top of said wall having screw-threaded holes 5-5 for the securing of various fittings, such as

rosettes, brackets or receptacles or a cover. The stud 3 is so short as not to interfere with the wiring of any fitting even though the bottom thereof is flat. In line with these lugs but removed therefrom so as to be axially accessible are two screw-holes 6-6 for screws for securing the box to a beam or joist. Upon one side of the line connecting these screw-holes and lugs are two large knock-out holes 7-7, so located that they are removed for a substantial distance from said stud and from said line, the angles between said line and the radii passing through the center of said stud and the centers of said large holes respectively being greater than 45°. The spaces between said knock-out holes and said wall stud and screw-holes are sufficient to permit the use of lock nuts 8 and bushings 9 on conduits and connectors and the screwing of a fixture on said stud. This results in having these large knock-out holes sufficiently removed from the lugs so that the lugs will not interfere with the use of the ordinary lock nuts 8 and bushings 9 on iron conduits 10 or cable connectors 11 when passed through said holes, the exposed internal flat bottom of the box extending to a circle in line with the axis of said stud and of substantially the same diameter as the screw-threaded portion of said stud, and also results in having these knock-out holes so located that the outlet box can be secured to a beam or joist 12 by screws passed through said screw-holes and yet leave the large knock-out holes uncovered so that the cables or conduits can be passed through them and secured in place. On the other side of the line connecting said screw-holes are two small knock-out holes 13-13, so located that they are removed for a substantial distance from the adjacent common tangent of said screw-holes, the result being that these small knock-out holes are also located so that the box can be secured to a beam by screws which pass through said screw-holes and yet leave the small knock-out holes uncovered. 13'-13' are knock-outs in the small holes. Where both large knock-out holes are opened the box can be used either for connecting a fitting or fixture or for an extension connection leading to another point.

In addition to the two screw-holes above mentioned there are two other screw-holes 14-14, which are located in a line substan-

tially at right angles to the line connecting the screw-holes first mentioned. When the outlet box is secured to a beam by screws passing through the two first mentioned screw-holes 6—6, one of the other holes 5 14—14 is opposite the beam and a third screw is passed through that hole so as to more securely fasten the box to the beam.

The box is a shallow round box three 10 quarters of an inch high. The box may be described as a universal box, since the knock-out holes therein described are adapted to take all commercial cables and conduits, the small holes being adapted to receive what 15 are known as circular loom cables, while the large holes are adapted to receive flexible conduit conductors and iron conduits or the B. X. cable. The lugs 4—4 are adapted to receive screws for holding all standard fittings and coverings, while the integral screw-threaded stud 3 is adapted to receive fixtures of various kinds and yet does not by its presence interfere with the use of any 20 standard fitting or a flat cover. The lugs 25 4—4 do not extend to the top of the wall 2, thus making it easier to insert the screws 15—15 which secure the fitting.

By my invention, the adding or removal 30 of a screw-threaded stud is unnecessary, since where a stud is unnecessary, my stud is of such length as not to be in the way, since it is low enough not to interfere with a flat base fitting 16 or a flat cover and is short enough to permit conductors to be 35 passed above it and through the holes in a flat base fitting. The use of a stud of the proportions mentioned, together with the peculiar relation of the knock-out holes, screw-holes and lugs, results in a device having 40 a large range of uses, so that it does not have to be replaced in case it is desired to use a fixture or fitting different from that originally intended.

As will be evident to those skilled in the 45 art, my invention permits of various modifications without departing from the spirit thereof or the scope of the appended claims.

What I claim is:

1. An article of manufacture consisting 50 of a shallow metal outlet box having a bottom, a circular wall, a central screw-threaded stud having sides substantially in line with its screw-thread and rising abruptly from said bottom, and two diametrically dis- 55 posed internally projecting lugs extending from said bottom approximately to the top of said wall, all formed of a single casting and integral with each other, said bottom having a pair of screw holes located re- 60 spectively on opposite sides of said stud and removed from said lugs so as to be axially accessible, two large conductor holes located on one side of the line connecting said screw holes, said large conductor holes being re- 65 moved for a considerable distance from said

line and from said stud, wall and pro- 70 jections, the angles between said line and the radii passing through the center of said stud and the centers of said large holes re- spectively being greater than 45°.

2. An article of manufacture consisting 75 of a shallow metal outlet box having a bottom, a circular wall, a central screw-threaded stud having sides substantially in line with its screw-thread and rising abruptly from 80 said bottom, and two diametrically disposed internally projecting lugs extending from said bottom approximately to the top of said wall, all formed of a single casting and in- 85 tegral with each other, said bottom having a pair of screw holes located respectively on opposite sides of said stud and removed from said lugs so as to be axially accessible, two large conductor holes located on one side of the line connecting said screw holes and two 90 smaller conductor holes located on the other side of said line and removed therefrom, said large conductor holes being removed for a considerable distance from said line and from said stud, wall and projections, the an- 95 gles between said line and the radii passing through the center of said stud and the centers of said large holes respectively being greater than 45°.

3. An article of manufacture consisting 100 of a shallow metal outlet box having a bottom, a circular wall, a central screw-threaded stud having sides substantially in line with its screw-thread and rising abruptly from said bottom, and two diametrically disposed in- 105 internally projecting lugs extending from said bottom approximately to the top of said wall, all formed of a single casting and in- 110 tegral with each other, said bottom having a pair of screw holes located respectively on opposite sides of said stud and removed from said lugs so as to be axially accessible, two large conductor holes located on one side of the line connecting said screw holes and two 115 smaller conductor holes located on the other side of said line and removed therefrom, said large conductor holes being removed for a considerable distance from said line and from said stud, wall and projections, the an- 120 gles between said line and the radii passing through the center of said stud and the centers of said large holes respectively being greater than 45°, and two other screw holes 125 in a line passing through said stud at right angles to the line connecting said other screw holes and also removed from said lugs so as to be axially accessible.

4. An article of manufacture consisting 130 of a shallow metal outlet box having a bottom, a circular wall, a central screw-threaded stud having sides substantially in line with its screw-thread and rising abruptly from said bottom, and two diametrically disposed in- 135 internally projecting lugs extending from said bottom approximately to the top of said

wall, all formed of a single casting and integral with each other, said bottom having a pair of screw holes located respectively on opposite sides of said stud and adjacent to and between said lugs and also having a pair of screw holes each adjacent to said wall and spaced substantially ninety degrees from said other screw holes, and also two large conductor holes for armored conductors lo-

cated on one side of the line connecting the 10 screw holes between said lugs and removed for a considerable distance from said line and screw holes and from said stud and wall, and also two smaller conductor holes located on the opposite side of said line and removed 15 therefrom and from said screw holes.

ALBERT GUTH.
